UNITED STATES PATENT OFFICE.

CHARLES ARDLEY SHEDAKER, OF PHILADELPHIA, PENNSYLVANIA.

UNION SUIT.

1,137,430.

Specification of Letters Patent. Patented Apr. 27, 1915.

Application filed July 21, 1914. Serial No. 352,171.

To all whom it may concern:

Be it known that I, CHARLES ARDLEY SHEDAKER, a citizen of the United States, residing at Philadelphia, in the county of Philadelphia and State of Pennsylvania, have invented certain new and useful Improvements in Union Suits, of which the following is a specification.

My invention relates to underwear and has particular reference to improvements in union suits of the type shown in Letters Patent granted to Algernon E. Clarke under date of August 13, 1912, Patent No. 1,035,819.

An important object of the invention is to increase the comfort of union suits, preferably those formed of relatively non-extensible material, such as cotton, mainsook, muslin, linen or the like, whereby the same will not bind or inconvenience the wearer in the crotch, when stooping or moving the legs; to thus improve the construction of a union suit without materially increasing the cost of manufacture thereof; to provide a garment of the above mentioned character which besides being convenient and comfortable, is cool; and to provide a garment of the above mentioned character, which is simple in construction, inexpensive to manufacture, strong, and durable.

A further object of the invention is to provide a union suit formed of relatively non-extensible material and having a crotch formed of highly vertically elastic and of sufficient area so that the ordinary vertically elastic waist band may be dispensed with, without inconvenience to the user.

Other objects and advantages of the invention will be apparent during the course of the following description.

In the accompanying drawings forming a part of this specification and in which like numerals are employed to designate like parts throughout the same, Figure 1 is a front elevation of a union suit embodying the invention, Fig. 2 is a rear elevation of the same, and, Fig. 3 is a fragmentary front elevation of the lower portion of the same, with the legs spread apart.

In the drawings, wherein for the purpose of illustration is shown a preferred form of my invention, the numeral 5 designates the body portion of the union suit or garment, the same comprising front sections 6, and a back section 7, stitched together at their outer adjacent edges, as shown at 8. The body portion 5 is provided with the usual

arm and neck holes 9 and 10, as shown. One of the front sections 6 is provided at its inner edge with a longitudinally extending forward flap 11 to normally cover the forward opening 11' and having button-holes 12, to receive buttons 13, secured to the other front section 6, whereby these two front sections are detachably connected and may be separated when desired. The flap 11 extends downwardly in proximity to the elastic crotch, as shown.

The numeral 14 designates legs of the union suit, formed of front and rear leg-sections 15 and 16, stitched together at their contiguous edges, as shown at 17 and 17'. The front leg-sections 15 are integral with or formed by a continuation of the front body-sections 6, while the rear leg-sections 16 are connected or stitched to the rear back section 7, as shown at 18. Preferably arranged below and adjacent the back waist stitching 18, is a posterior opening 19, adapted to be closed by a posterior flap 20, carried by one of the rear leg-sections 16. This flap is provided with a button hole 21' to receive a button 21, in turn attached to the other rear leg-section 16, whereby the flap 20 may be detachably connected with such rear leg-section.

The numeral 24' designates a vertically elastic or yieldable forward crotch insert or gusset, preferably formed of a knit fabric, having its wales running substantially horizontally or longitudinally of the same and preferably arranged wholly upon the forward side of the inner leg-seams 17 and extending up to and being contiguous with the forward flap 11, as shown.

The numeral 25 designates a rear crotch insert or gusset which is vertically elastic or yieldable and preferably formed of a knit fabric having its wales extending substantially longitudinally or horizontally of the same. This insert or gusset is preferably arranged wholly upon the rear side of the seams 17 and is formed in sections 26, having their inner ends separated and overlapping, as shown, to provide a continuation of the posterior opening 19.

The forward and rear inserts 24' and 25 are attached together by a continuation of the seam or seams 17. By this construction a vertically yieldable crotch insert is provided having the maximum area, whereby the strains or pulls are taken up in a most satisfactory manner.

If it is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:—

1. In a union suit of the character described; a body portion having a front opening; a lower portion carried by the body portion and comprising legs having inner longitudinal seams, the rear portions of the legs being separated and overlapping for forming a normally closed posterior opening; a vertically yieldable crotch insert tapered toward its ends, arranged between the legs wholly rearwardly of the inner seams thereof and attached to the legs; and a second vertically yieldable crotch insert tapered toward its ends, arranged between the legs forwardly of the first named crotch insert, and attached to the legs and the first named insert, such attachment with the first named insert forming a continuation of the inner seams of the legs.
2. In a union suit of the character de-

scribed; a body portion having a front opening; a lower portion carried by the body portion and comprising legs having inner longitudinal seams, the rear portions of the legs being separated and overlapping for forming a normally closed posterior opening; means for detachably connecting the overlapping rear portions of the legs; a vertically yieldable crotch insert tapered toward its ends and arranged between the legs wholly rearwardly of the inner seams and attached to the legs, said vertically yieldable crotch insert including a plurality of separate overlapping sections forming a continuation of the normally closed posterior opening; and a second vertically yieldable crotch insert tapered toward its ends, arranged between the legs forwardly of the first named crotch insert, and attached to the legs and the first named insert, such attachment with the first named insert forming a continuation of the inner seams of the legs.

In testimony whereof I affix my signature in presence of two witnesses.

CHARLES ARDLEY SHEDAKER.
